Primary Examiner—Stacia Cadmus

(74) Attorney, Agent, or Firm—G. Donald Weber, Jr.

(57) **CLAIM**

The ornamental design for an automotive wheel, as shown and described.

DESCRIPTION

FIG. 1 is a perspective view of a first embodiment of the automotive wheel of the instant invention.

FIG. 2 is a side elevation view of the first embodiment of the automotive wheel of the instant invention.

FIG. 3 is a perspective view of a second embodiment of the automotive wheel of the instant invention; and,

FIG. 4 is a side elevation view of the second embodiment of the automotive wheel of the instant invention.

The broken line showing of environment is for illustrative purposes only and forms no part of the claimed design.
